[57] CLAIM

The ornamental design for a golf putter head, as shown and described.

DESCRIPTION

FIG. 1 is a perspective view of a golf putter head showing a right-hand embodiment of my design;
FIG. 2 is a top plan view of FIG. 1;
FIG. 3 is a perspective view of a golf putter head showing a left-handed embodiment of my design;
FIG. 4 is a top plan view of FIG. 3;
FIG. 5 is a front elevational view of FIGS. 1 and 3;
FIG. 6 is a right elevational view of FIGS. 1 and 3, the left side being a mirror image thereof;
FIG. 7 is a bottom plan view of FIGS. 1 and 3;
FIG. 8 is a rear elevational view of FIGS. 1 and 3; and,
FIG. 9 is a cross section taken on line 9—9 of FIG. 7.
